Inventor,
G. Overhiser

UNITED STATES PATENT OFFICE.

G. C. OVERHISER, OF BINGHAMTON, NEW YORK, ASSIGNOR TO HIMSELF
AND GEO. W. GREGORY, OF SAME PLACE.

IMPROVEMENT IN OIL-CANS.

Specification forming part of Letters Patent No. 44,485, dated September 22, 1864.

To all whom it may concern:

Be it known that I, G. C. OVERHISER, of Binghamton, Broome county, New York, have invented a new and useful Improvement in Oil-Cans; and I do hereby declare that the following is a full and exact description thereof, reference being had to the accompanying drawings, and to the letters marked thereon.

Similar letters denote like parts.

Figure 1 is a perspective view of my can. Fig. 2 is a sectional view.

In order that others skilled in the arts may understand my invention, I will proceed to describe its construction and operation.

A is the body of the can; B, the spout or tube, and is screwed into the can at *g*. C is a lever, which is operated by the thumb. One end is fastened to the can at *h*. A short distance from this fixed point there is fastened a wire, *c*, to the under side of the lever. This wire extends through a hole into the can, and has upon its inner end a ring or washer of leather or rubber, *O*. The hole is for a vent, and the washer is for stopping it. A little farther out on this lever I place another bent rod or wire, *b*, which I loop over the crooked end of the rod *D*. This rod passes up and along the tube *B*, through guides *a a*, and is fastened at its upper end to a sliding tube or collar, *F*, which fits close to the tube *B*, and is allowed to slide up and down upon it. This tube or collar has a small spout, *d*, through which the oil passes out. I make a hole, *G*, Fig. 2, in the main tube *B*. The tube or collar is provided with a corresponding hole, *x*. Encircling the rod *D* is a spiral spring, *E*. One end of the spring is fastened to the rod and the other end rests upon one of the guide-eyes *a*. By the action of this spring upon the rod *D* the collar *F* is moved up and held, so that the hole *x* is above the hole *G*, the bottom of the collar covering the hole *G*, thus preventing the escape of the oil. Now, when the can is turned down in a horizontal position, the tube *B* is filled with oil, but cannot escape, as the holes in the tubes *F* and *B* are not opposite. When you wish to discharge the oil, press the lever-piece *C* down, as shown in red lines, Fig. 1, which also brings down the collar *F*, so that the holes *x* and *G* correspond or are opposite. The descent of the

lever also pushes the piece *O* from the vent, and allows a free escape or flow of oil. Remove the pressure from the lever *C* and the spring *E* immediately returns the collar *F* and washer *O* to their former positions, stopping the flow of the oil instantly. With the cans now in use much of the oil is wasted, as they are unable to control so quickly or effectually the flow of the oil. I can drop as little or as much oil as desired, and right to the point. I also deem it very desirable to place the operating parts of an oil-can upon the outside instead of the inside, as is usually done, and thus keep the inside for oil instead of machinery.

I do not wish to limit myself to just such a sliding collar and spout as I have described, as I can accomplish the purpose desired as effectually by placing the spout a little higher up on the sliding collar *F*, and place the cap over the collar instead of the tube, so that when the collar is elevated the hole *x* is brought above the open top of the tube *B*, and the oil is allowed to escape. In this modification of my can, I can change the fulcrum of the lever-piece *C* to a point near the center, and place the loop *b* on the inner end, and the spring is made to operate against the upper guide eye or rest *a*.

Having described my invention, what I claim, and desire to secure by Letters Patent, is—

1. The sliding collar, as described, with or without the spout, in combination with the tube of the can.
2. The rod *D*, acted upon by a spring, in combination with the sliding collar, for the purpose herein described.
3. The combination of the lever, the wire with the washer, and the spring for closing the vent.
4. The lever *C* and loop *b*, in combination with the rod *D* and sliding collar for controlling the discharge of the oil, as described.
5. The sliding collar and spout, in combination with the rod *D*, spring *E*, lever *C*, and can, as and for the purpose described.

G. C. OVERHISER.
